UNITED STATES PATENT OFFICE.

CONRAD GOEBERT AND OTTO KUGLER, SR., OF PHILADELPHIA, PENNSYLVANIA, AS-
SIGNORS TO OTIS ELEVATOR COMPANY, OF JERSEY CITY, NEW JERSEY, A COR-
PORATION OF NEW JERSEY.

ELEVATOR-CONTROLLING DEVICE.

Application filed June 14, 1923. Serial No. 645,299.

This invention relates to elevators and more particularly to means for effecting a positive stopping of the elevator at predetermined positions automatically, the same being principally useful for effecting a stopping of the elevator platform at the various floors.

Another object is to provide the combination of an elevator car with means to raise and lower the same, motor-driven means to effect said raising and lowering, electrical means for regulating said last-named means, fixed means corresponding with the position of the floors at which the elevator is adapted to stop, and means carried by the elevator and co-operating with said fixed means, whereby through suitable electric circuits the motor is stopped so that the elevator altitude thereby governed is arrested at predetermined positions.

A further object is to provide such a construction and operation as the foregoing, as a result of which the stopping of an elevator will uniformly and permanently be substantially in exact accordance with the positions of the respective floors, regardless of the expansion, contraction or stretching of the elevator-supporting cable or other means, regardless of the angular position or number of rotations of the cable-drum or the like, as the case may be, or of any other elements extraneous to the elevator itself and the said fixed means.

Still another object is to provide the combination with the foregoing structure, means for operating the elevator at two or more speeds, and so constructing and arranging the stopping means and the fixed means that the co-operation of the stopping means with said fixed means automatically changes from one speed to the other at predetermined positions or intervals with regard to the various floor positions.

And a still further object is to provide suitable electro-magnetic or manually-actuated means for re-setting the stopping device, so that the motor for driving the cable-drum or sheave may thereupon be made to restart the movement of the elevator either up or down as may be desired.

And yet another object is to provide the improved automatic stopping device and fixed member in combination with manually-actuated means for controlling the starting

and stopping of the elevator independently of the said device, and so arranged that by a further movement of said manually-actuated means the said stopping device is either mechanically or electrically thrown into operative position so that it will function automatically to arrest the movement of the elevator independently of the said manually-actuated means. In this construction, the latch or equivalent mechanism is provided in the stopping device, whereby the contact-board is maintained in a given position, while the manually-actuated means and the sliding-bar of the stopping device return to their original positions, whereupon a cam or its equivalent carried by said bar actuates the latch to release the contact-board, so that the latter re-establishes the circuits passing through the stopping device, this being for the purpose of preventing the re-starting of the elevator before such is intended as the manually actuated means is being returned to its neutral position.

With these and other objects in view, the present invention comprises further novel details of construction and operation herein-after fully brought out in the following description, when read in conjunction with the accompanying drawings, in which Fig. 1 illustrates diagrammatically a typical two-speed automatic push-button controlled elevator, together with our improved stopping apparatus; Fig. 2 is an enlarged detail view of the stopping device, comprising certain of the mechanical features of the invention; Fig. 3 is a modified arrangement of electric circuits controlled by a car-switch, together with the improved stopping apparatus; and Fig. 4 is a view of the mechanical elements of Fig. 3, and shown in substantially the same manner as Fig. 2.

The electric hoisting motor M may be connected to the elevator car C through any of the well-known systems. The motor illustrated herein is of the compound wound type, it being provided with a series and shunt field winding, S and S', respectively. A usual or standard type electro-mechanical brake B is employed in which a brake-shoe 1 is applied to stop the car by means of a spring 2, and released by means of an electro-magnet 3.

Electro-magnet reversing switches for the

elevator motor M are designated D and U, D controlling the motor for the descending travel of the car, and U for ascending. The mode of operating the reversing switches by means of solenoids is well known and common practice, therefore further explanation is believed to be unnecessary. An accelerating magnet F operates in a well known manner to cut out the motor starting resistance 10 E and series field winding S. A speed device V also operates in a well known manner to increase and decrease the speed of the motor.

Different landings or stopping points are 15 designated L, L' and L'', car push-buttons 4, 4', 4'', hall push-buttons, 5, 5', 5'', door contacts d, d', d'', floor magnet relay switches 6, 6', 6'', non-interference magnet 7, car-holding magnet 8, floor controller switches 9, 9', 9'', 9''. The elements thus far described are well known and have a well-known mode of operation.

Electrical mains supplying a relatively 20 high voltage, say for example, 220 or 440 volts, are designated + and -.

Operation of the apparatus as a whole and through a complete cycle of operation will now be given.

With the parts as illustrated in the drawing, the car is at rest, level with the second floor landing. Let us assume now that it is desired to bring the car to the first floor landing, by pressing the car push-button 4. This operation closes a circuit for the winding 14 of the reversing switch D, as follows: From + main, to wire 15, through the door contacts to wire 16, one winding of the non-interference magnet 7 to wire 17, winding of protecting magnet 8 to wire 18, push-button 4 to wire 60, through winding of floor magnet 6 to wire 19, through floor controller contacts 9 to wire 20, to wire 20½, through reversing switch coil 14 to wire 21 to wire 21½, to wire 22, through auxiliary contacts 23 on the third accelerating hammer (which is at rest due to not yet being in operation) to wire 24, to the - line.

In order to maintain a circuit for the reversing switch coil 14 when the car push button is released, a second circuit is automatically formed by the current coming through the one winding of the non-interference magnet 7 in the same manner as heretofore mentioned and thence to wire 25, through magnet coil 25½ (the object of which will be defined later) to wire 26 and through the contacts of relay 6 (which are already closed by the former operation) and thence to wire 19 through floor controller contacts 9 to wire 20, to wire 20½, through coil 14 to wire 21, to wire 21½, now through the normal operation of the accelerating switch, the circuit through contacts 23 is broken, consequently the circuit continues through wire 21½ to contact 26, to contact

27, to contact 28, to wire 29, and the - line. It will be mentioned here that when the coil 25½ was energized as aforesaid, it reset the car stopping device, so that the circuit just described as well as the circuit for the speed 70 magnet V described later could be made.

With the car stopping device herein described, it will also be necessary to maintain another circuit for the reversing switch coil 14 after the floor controller contacts are automatically broken through normal operation. This circuit is also automatically formed by the current coming through the one winding of the non-interference magnet 7 in the same manner as heretofore mentioned, and thence to wire 17 to wire 46, through auxiliary contacts 47, on reversing switches to wire 48, to wire 20½, through coil 14, wire 21, wire 21½, contact 26, contact 27, contact 28, wire 29, and - line.

The winding 14 now receiving current closes the reversing switch with all its contacts with the exception of contacts 34½ which are broken during this operation and the elevator motor M, field winding S and S', and brake winding 3 are thereby connected to the high voltage mains + and -. The motor circuit may be traced as follows: From the + main through contact 30 and insulated contact 30½, to wire 31, contacts 32, to wire 33, through motor M to wire 34, through one contact 34½ on reversing switch arm, through reversing switch arm D, contacts 35, wire 36, through starting resistance E and series field winding S to - line. The shunt field and brake circuits are closed through auxiliary contacts 37 controlled by the reversing switch. The brake shoe 1 is now released by the magnet 3, and the motor M rotates to start the car in a descending direction, the motor being gradually accelerated to its first speed by the operation of the accelerating magnet F in gradually cutting out the starting resistance and series field winding. The current for energizing accelerating magnet coil F is obtained through wire 39 which is connected to contacts 38 on the reversing switch D.

In order to obtain the second or full speed of the motor, a series of resistance 12 is placed in shunt field circuit thereby weakening the fields. This method for increasing the speed of the motor as well as decreasing the speed is well known and standard practice, therefore, it is thought sufficient only to define the circuit which controls the speed magnet V. The reversing switch D being closed, forms a circuit as follows: From contact 38, to wire 39, to wire 40, through speed magnet coil V to wire 41, through contacts 42 on the fourth accelerating hammer (which is now closed through normal operation mentioned heretofore), to wire 43, to contact 44, through contacts 45, to contact 46, to wire 47, and the - line.

It will probably be well to mention that the non-interference magnet operates to open its contacts and thereby open circuits the wire 7' to the hall push-buttons and the relay 8 operates to close its contacts and so prevents operation of car by the hall buttons until after the car is stopped, the hatchway door opened and again closed. The above statement for the function of the elements 10 7 and 8 is thought sufficient, since the circuits controlled thereby are well known.

The elevator car now descends, and just before stopping device G on car comes within the range of hatchway incline 13^a, the 15 floor controller is set so that in performing its regular function it breaks its contacts 9 and thereby opens the circuit to coil 25½ and releases sliding bar 54 of stopping device G, said bar is forced out by spring 10 20 so that roller 11 will engage hatch incline 13^a. In doing so, the contact board 51 is pulled forward slightly or just sufficient to break the circuit between contacts 44 and 46, thereby releasing magnet coil V, which in 25 turn allows the speed device to perform its regular function of decreasing the speed of the motor. The car still continuing to descend, now comes in range of hatchway incline 14^a which engages roller 11 and the 30 contact board is again pulled forward so that the circuit between contacts 26 and 28 is broken, thereby releasing coil 14 which allows the reversing switch to drop to its initial position, and in this manner the electrical circuits controlled thereby to the 35 motor, brake winding, etc., are opened and the brake shoe is applied to bring the elevator car to rest.

The essential elements of the push-button 40 system and the elevator stopping apparatus operate, conjointly, to control the elevator car for ascending direction of travel substantially in the same manner as has just been described for the descending direction 45 of travel, these elements furthermore, operating to control the car, in the same manner for both the car and hall push-button operations. It is therefore thought that a 50 detailed description for these modes of operation is unnecessary.

The construction of the stopping mechanism for controlling the stopping of the car at the desired floor, is shown in Figure 2 and 55 consists essentially of the contact board 51 constructed of insulating material and carrying the elongated contact plate 27 for bridging between contacts 28 and 26, and the oppositely disposed and interconnected plates 45 for bridging the contacts 44 and 46. The board 51 is movably supported by a bar 50 which may be of metal. A spring 52 tends 60 to reset the contact board when coil 25½ is energized for operation. The bar 50 is slideable in bearings 53 of any suitable construction.

There is a second bar indicated at 54 which underlays both the bar 50 and the contact board 51, but which is slidably mounted also in bearings 53. The one end of this bar 54 is attached to core of the magnetic coil 25½, so that when the latter is energized, the bar 54 will be drawn inwardly 70 out of co-operative relation with the inclines 13^a and 14^a in the hatchway. When coil 25½ is not energized spring 10 tends to 75 force the bar 54 outwardly into co-operative relation with the hatchway inclines. Pivotally mounted on the outer end of the bar 54 is a lever 56 which carries a roller 11 at one end and which is pivotally connected at 80 the other end with a link 57 the inner portion of which is slotted at 58 and connected with the bar 50 by a pin 59 passing through the slot 58.

The operation of this mechanism is as follows: When any button is pushed to start the car, the solenoid or coil 25½ is energized thereby drawing in bar 54 and permitting bar 50 to move the contact board 51 by means of spring 52 so as to close the circuits. The car progresses to within a pre-determined distance of the desired floor when the circuit through the solenoid 25½ is automatically broken thereby releasing the bar 54 which is moved outwardly by spring 10 until the stops 60 and 61 prevent further movement. This has moved link 57 the length of the slot 58 but has taken no effect on the contact board 51. The roller 11 is now in co-operative relation with the inclines 13^a and 14^a and as it rides up the former, the link 57 is moved to slide the board 51 sufficiently to break the circuit through contacts 44, 45 and 46. As above 95 explained, this effects a slowing down or retardation of the speed of the car. Roller 11 then rides up the incline 14^a and thereby shifts the board sufficiently to break the circuit through the contact members 26, 27 and 28, so that the power is shut off and the 100 brake is applied as above mentioned which effects the complete stopping of the car.

In the form shown in Figures 3 and 4, there is used a large part of the same wiring and mechanism as in the push-button type, and such parts and wires are designated with the same numerals as in the former instance. The parts which vary from the former part of the disclosure will now be described in detail.

The type of elevator here dealt with is that known as the car switch controlled elevator and is intended to be operated manually from a switch H within the car. The 115 essence of the invention as applied to this type of elevator is to provide means whereby the operator after selecting the floor at which he desires to stop the car, causes the actual stopping to be done automatically. 120 This requires no skill on the part of the 125 130

operator and at the same time effects a uniform stop.

The switch H is provided with a weighted self returning lever 75 and has attached on one end a lateral spindle, on which is mounted a handle 76.

There is also attached to lever 75 an insulated pivoted segmental contact 78, which engages contacts 79 and 79', both of which are connected to the plus main by means of wire 15. There are also mounted in the switch down contact 80 and up contact 81, and full speed contacts 82 and 82', which are connected together by wire 83.

15 The switch just described is standard equipment and the mode of operation is well known.

The frame 77 of switch H is provided with the usual limiting shoulder 90 for limiting 20 the movement of handle 76 in either direction in effecting the elevating or lowering the car. It is, however, desirable in a mechanical embodiment which is shown and described later to be able to move the handle 76 beyond this usual limit to shoulder 95 in order to set the stopping mechanism to break the circuits and stop the car at the predetermined position.

30 The stopping device G itself for car switch controlled elevators is somewhat modified in that it has an additional set of contacts for the up motion, same being numbered 98-99-100. When the car is at rest, all the contacts on stopping device are made 35 ready for operation, whereas with the stopping device for push-button elevators the contacts are open when elevator is at rest. The slideable bar 54 instead of being controlled by a solenoid as in the case of the 40 push-button, elevator is controlled by mechanical means as follows.

Attached to the lever 75 in the switch H is pivoted a depending link 84 having at 45 its lower end a slot 85, in which there rides a pin 86 extending laterally from one arm of bell crank 87 conveniently mounted in proper relation to operate the bar 54. One of the arms of lever 87 is connected with the bar 54 by a pin and slot connection 88.

50 With the parts as illustrated in the drawing, the car is at rest, level with the second floor landing. Let us assume now it is desired to bring the car to the first floor landing. The operator pulls the handle 76 outward in order to allow same to pass the shoulder forming the hollow portion of frame 77, and moves said handle clockwise to the right until contact 78 bridges contacts 79 and 80, this forms a circuit for reversing 55 switch coil 14 as follows. From + main to wire 15, contact 79, contact 78, contact 80, wire 89, contact 26, contact 27, contact 28, wire 20, coil 14, wire 21, wire 21½ to - line. The coil 14 now receiving current closes the 60 reversing switch with its contacts and the 65

elevator motor M, field windings S and S' and brake winding 3 are thereby connected to the high voltage mains + and -. The circuits formed by the contacts on the reversing switch when closed were cited in defining 70 the operation of the push-button elevator, therefore it is unnecessary to describe them again.

While performing the operation just mentioned, the operator allows the handle 76 75 to resume its normal relation to the lever 75 and at the same time continues to move the lever 75 clockwise until it reaches shoulder 90 on frame 77, thereby allowing contact 78 to also bridge contact 82. This forms 80 the circuit for the speed device coil as follows. From + main to wire 15, contact 79, contact 78, contact 82, wire 83, wire 91, contact 46, contact 45, contact 44, wire 92, auxiliary contacts 42 on fourth hammer of accelerating switch F, wire 93, coil V; wire 94, to - line. This circuit being completed, the speed device performs its function of increasing the speed of the motor, the same as mentioned in the specification for the 90 push-button elevator.

The elevator car now descends and before stopping device G comes within range of incline 13^a, the operator again pulls handle 76 outward in order to allow same to avoid 95 shoulder 90 and again he moves handle 76 clockwise to finally stop shoulder 95. In doing so, all the circuits made in the car switch and as well as the circuits on the stopping switch G remain intact. The segmental contact 78 in the car switch is made 100 large enough to bridge contacts 79 and 82 even with the additional movement of the handle 76 which effects the stopping of the elevator hereafter brought out.

When the handle 76 was moved to its final stop shoulder 95, the lever 75 raised link 84 so that the lower end of the slot 85 engaged pin 86 and operated bell crank lever 87 to move the slideable bar 54 outwardly, thereby bringing roller 11 into co-operative relationship with inclines 13^a and 14^a and as these inclines are reached the stopping device G is operated similarly to the manner described in connection with the push-button elevator so as to break the circuits which have been formed and ultimately effecting a complete stop of the elevator.

In order to use the stopping device G in connection with bar switch controlled elevators, it is necessary to provide a spring-operated latch arrangement to hold the contact board 51 in the outward position after the circuits formed by its contacts are broken. This is done so as to prevent any 120 circuit being formed through the car switch contacts while the lever 75 is being returned to its normal position when the elevator is at rest. The lever 75 automatically resets link 84, lever 87, and slideable 125 130

bar 54. In resetting bar 54, cam 96 mounted on the same raises latch 97 and releases contact board 51, which resets itself by means of spring 52 for another operation. The cam 5 96 is arranged on bar 54 so as to perform its function of raising latch 97 just prior to the lever 75 assuming its initial position on centre or directly after contact 78 in car switch has disengaged contact 80.

10 The essential elements of the car switch system and the stopping apparatus operate, conjointly, to control the elevator car for ascending direction of travel substantially in the same manner as has just been described 15 for the descending direction of travel. It is therefore thought that a detail description for this mode of operation is unnecessary.

While we have described what we deem to be the most desirable embodiment of our 20 invention, it is obvious that many of the parts may be varied without in any way departing from the spirit of our invention, and we therefore do not limit ourselves to the exact details of construction herein shown, 25 nor to anything less than the whole of our invention limited only by the appended claims.

Having thus described our invention, what we claim and desire to protect by Letters 30 Patent of the United States is:—

1. An electric elevator system comprising, a car switch operable from off position to a position to cause the starting of the car and being movable in the same direction from off 35 position beyond the starting position to a stop position, and means for causing the stopping of the car upon movement of said car switch into stop position.

2. An electric elevator system comprising, 40 a car switch operable from off position to a position to cause the starting of the car and being movable in the same direction from off position beyond the starting position to a stop position, and means for bringing the 45 car to a stop level with a landing upon movement of said car switch into stop position.

3. An electric elevator system comprising, 50 a car switch operable from off position to a position to cause the starting of the car and being movable in the same direction from off position beyond the starting position to a stop position, and means for causing the stopping of the car upon movement of said 55 car switch into stop position and, once the car switch has been moved into stop position, for preventing the control of the car by said car switch until after it has been returned to off position.

60 4. An electric elevator system comprising, a car switch operable from off position to a position to cause the starting of the car and being movable in the same direction from off 65 position beyond the starting position to a stop position, and means for causing the

stopping of the car upon movement of said car switch into stop position and for preventing restarting of the car upon movement of said switch into starting position unless it is first returned to off position. 70

5. An electric elevator system comprising, a car switch carried by the car and operable from off position into an operative position to cause the starting and running of the car, 75 said switch being movable beyond said operative position, and a stopping switch also carried by the car and movable by said car switch, upon its movement beyond said operative position, into a position for causing the car to be brought to a stop level with a 80 landing.

6. An electric elevator system comprising, a car switch carried by the car and operable from off position into an operative position to cause the starting and running of the car, 85 said switch being movable beyond said operative position, switching mechanism also carried by the car and having a position for permitting the starting and running of the car, and means connecting said car switch 90 and said switching mechanism for causing, upon movement of said car switch beyond said operative position, movement of said switching mechanism into position for causing the car to be brought to a stop level with 95 a landing.

7. An electric elevator system comprising, a car switch carried by the car and operable from off position into an operative position to cause the starting and running of the car, 100 said switch being movable beyond said operative position, switching mechanism also carried by the car and having a position for permitting the starting and running of the car, means connecting said car switch and 105 said switching mechanism for causing, upon movement of said car switch beyond said operative position, movement of said switching mechanism into a second position without interrupting the running of the car, and means cooperating with said switching mechanism, upon its being moved into said second position, to cause the car to be brought to a 110 stop level with the desired landing.

8. An electric elevator system comprising, a car switch having an off position and being movable in one direction from off position into an operative position to cause the starting and running of the car in one direction and in the other direction from off position into an operative position to cause the starting and running of the car in the other direction and being further movable beyond its operative positions in each direction, and means for causing the stopping of the car 115 at a landing upon movement of said car switch beyond either operative position.

9. An electric elevator system comprising, a car switch movable from off position into one operative position and, upon continued 120

movement in the same direction, into a second position, means for causing the starting of the car, upon movement of said switch into said one operative position, and for causing the stopping of the car at any point, upon the return of said switch into off position, and means for causing the car to be brought to a stop automatically at a landing upon movement of said switch into said second position.

10. The combination of an elevator car, motor-driven means to raise and lower the same, electrical means for regulating said last-named means, fixed means corresponding with the positions of the floors at which the car is adapted to stop, means carried by the car and co-operating with said fixed means, whereby through suitable electric circuits the motor-driven means stops the car at substantially any predetermined altitude and the starting of the car is thereafter prevented, and means operative to reset said means carried by the car to permit the restarting of the car.

11. The combination of an elevator car, motor-driven means to raise and lower the same, automatic stopping means carried by the car, means fixed with respect to the hatch or shaft, manually-actuated means to control the speed and direction of said first means through suitable electric circuits, said manual means also being operative in one position to set the stopping means whereby upon the stopping means engaging the fixed means the car is brought to a stop at substantially a predetermined altitude and the starting of the car is prevented, said manual means upon being removed from said position to off position causing the resetting of the stopping means to permit the restarting of the motor-driven means.

12. The combination of an elevator car, motor-driven means to raise and lower the same, automatic stopping means carried by the car, means fixed with respect to the hatch or shaft, manually-actuated means to control the speed and direction of said first means through suitable electric circuits, said manual means also being operative in one position to set the stopping means whereby upon the stopping means engaging the fixed means the car is brought to a stop at substantially a predetermined altitude and the starting of the car is prevented, said manual means also being operative to reset the stopping means to permit the restarting of the first means and car.

13. The combination of an elevator car, motor-driven means to raise and lower the same, automatic stopping means carried by the car, means fixed with respect to the hatch or shaft, manually-actuated means to control the speed and direction of said first means through suitable electric circuits, said manual means also being operative in one po-

sition to set the stopping means whereby upon the stopping means engaging the fixed means the car is brought to a stop automatically at substantially a predetermined altitude and the starting of the car is prevented, 70 said manual means upon being removed from said position to a given position causing the resetting of the stopping means to permit the restarting of the motor-driven means, and latch means to delay the complete resetting of the stopping means until the manual means substantially reaches said given position.

14. An electric elevator system comprising, a car switch for causing the starting of the car, switching mechanism carried by the car, means for moving said switching mechanism into a position to cause the stopping of the car, and means for latching said mechanism in its stopping position. 80

15. An electric elevator system comprising, a car switch for causing the starting of the car, switching mechanism carried by the car, means for moving said switching mechanism into a position to cause the stopping of the car, means for latching said mechanism in its stopping position, and means operable by said car switch, upon its movement into a given position, to release said latching means. 90

16. An electric elevator system comprising, a car switch for causing the starting of the car, switching mechanism carried by the car, means for moving said switching mechanism into a position to cause the stopping of the car, means for latching said mechanism in its stopping position to prevent restarting of the car, and means for releasing said latching means and for resetting said mechanism to permit restarting of the car upon movement of said car switch into a given position. 100

17. An electric elevator system comprising, a car switch for causing the starting of the car, switching mechanism carried by the car, means for moving said switching mechanism into a position to cause the stopping of the car and to prevent the restarting of the car, said car switch being operable, upon movement into a given position, to cause the resetting of said switching mechanism into position to permit the restarting of the car, and latching means for preventing the complete resetting of said mechanism until said controller switch substantially reaches said given position. 110

18. The combination of an elevator car, motor-driven means to raise and lower the same, electrical means for controlling the operation of said last-named means, fixed means corresponding with the position of the elevations at which the car is intended to stop, a stopping device carried by the car and co-operating with the fixed means, whereby through suitable electrical circuits the motor-driven means stops the car as it 120 125 130

reaches a given elevation, said stopping device remaining in position to prevent restarting of the car, and means for resetting the stopping device to permit restarting of the car.

19. The combination of an elevator car, motor-driven means to raise and lower the same, electrical means for controlling the operation of said last-named means, fixed means corresponding with the position of the elevations at which the car is intended to stop, a stopping device carried by the car and co-operating with the fixed means,

whereby through suitable electrical circuits the motor-driven means first decreases the speed of the car upon approaching a given elevation, and then stops the car as it reaches the said given elevation, said stopping device remaining in position to prevent restarting of the car, and means for resetting the stopping device to permit restarting of the car.

In testimony whereof we have affixed our signatures.

CONRAD GOEBERT.
OTTO KUGLER, SR.
